UNITED STATES PATENT OFFICE

FRANZ GRUTTMANN, OF COLOGNE, GERMANY

REGISTERING STAMP

Application filed October 28, 1926, Serial No. 144,854, and in Germany May 19, 1926.

This invention relates to registering stamps and more particularly to that kind having numeral setting and printing means, adapted to register and record the necessary items 5 for proper bookkeeping systems.

The invention has for an object to provide a portable hand actuated stamp whereby power given for causing the stamp to make an impression or print of the number registered thereon, will also be utilized for actuating the recording mechanism associated therewith.

An equally important object of the invention resides in the provision of a portable 15 registering machine that will quickly and accurately stamp or print the account number, the amount of money, the date, etc., upon almost any book, leaf, or form of known bookkeeping systems.

Another important feature of the invention consists in the provision of a registering stamp that will lock itself while in registering and recording operations, so that proper and accurate entries may be made, and when 25 released, will be automatically unlocked, thereby making it ready for the next operation.

Other important objects and advantages of the invention will be in part pointed out 30 and in part obvious to those skilled in the art as the description progresses.

The various objects of the invention are preferably obtained by the structure illustrated in the accompanying drawings, 35 wherein

Figure 1 is a vertical section through my improved registering stamp,

Figure 2 is a front elevation of the same having parts broken away,

Figure 3 is a perspective of the same,

Figure 4 is a book entry obtained by my improved device, and

Figure 5 is the adjoining type plates or disks forming such entry.

Referring now more particularly to the drawings wherein like characters of reference will designate corresponding parts throughout, my improved device may be stated to comprise a casing 2 preferably of the 50 shape and form shown, made of any suitable

material and having securely attached thereto a handle 1. Extending throughout the casing 2 and carried by the side walls thereof, is a shaft or axle 6 supporting a series of gears 5 having the levers 4 preferably formed integral therewith, projecting through the vertical curviform slots 3 in the front portion of the casing 2.

Meshing with the gears 5 are the gears 7 supported by the shaft 11 and carrying bands 60 15 having the numerals 0 to 9 inclusive adapted to register within the window 16 arranged within the front wall of the casing 2. Also meshing with the gears 5 are a series of gears 10 loosely mounted upon a shaft 14. This latter shaft 14 has fastened thereupon numeral carrying wheels and ratchet wheels 18. A pawl 19 engages the ratchet wheel 18 to permit rotation of the latter in one direction only and a locking pawl 20 for this 70 ratchet wheel is also provided. These latter parts form a portion of an adding mechanism so that the numerals upon the wheel 21 will register through the window 22 whereby the totals obtained will be visible.

Operatively connected to the gears 5 are type wheels 8 and 9 rotating on shafts 12 and 13 respectively, said wheels having on their outer periphery type faces 17, inked by the ink rolls 31 during the rotation of said wheels. These type wheels, as is clearly shown in the Figure 5, are formed in four distinct sections, section A being the non-registering consecutive number, section B a registering account number, section C a registering 85 book entry number and section D registering the date including the day, month and year.

As shown in the Figure 1 the upper type wheel 9 is adapted to print the registered items on the tape 23 carried within the casing 2 by means of the roller 24. This tape extends from the roller 24 over a guide roll 25, a pressure roll 26 and is to be wound upon a roller 27. This latter roller 27 has a ratchet wheel 28 attached thereto which is 95 engaged by a pawl 30 to limit rotation of said roller 27 in one direction only.

The type wheel 8 as shown in Figure 1, is adapted to print or register on a book, leaf or other form placed beneath the stamp through 100

the opening 39 in the bottom plate 32 of the casing 2.

Carried by the bottom plate 32 and extending within the casing are the spring housings 33 through which project the supporting legs 34, connected at their upper portions by means of the rods 35 and retained in their normal or projecting positions as is better illustrated in Figure 1 by suitable coil springs 10 arranged in the housings 33. Mounted on one rod 35 are the pawls 37 and 38 engaging the type wheels forming section A, whereby when movement is transmitted to the bars 35 the pawls will cause these type wheels to rotate which in turn will register the consecutive numbers thereon and record the number of times impressions were made. The shaft 36 connecting the rear supporting legs to the rod 35, also serves to support a pressure roll 26 which carries the tape 23 to the type wheels 9 when pressure is applied to the stamp. This shaft also carries the pawl 29 which by the spring action of the supporting legs will turn the ratchet 28 carried by the winding roll 27 thereby drawing the paper 23, making the same ready for the next operation.

When using my improved device, the levers 4 are first moved to the desired figures. Adjacent the slots 3 as are shown in Fig. 2 thereby causing to be registered within the window 16 the account number which latter is effected by the number of rollers of section B, the amount of the sale or purchase by the number rollers of section C and the date by 35 the rollers of section B. At the same time the adding mechanism is actuated so that the total amount of sales made will appear through the window 22. When these levers 4 are returned to their normal position as shown in Figure 3 the window 16 will be cleared of numerals whereas the total amounts of sales will still appear through the window 22. When pulling down on these levers 4 the type wheels 8 and 9 will also be rotated 45 whereby the numbers corresponding with those shown through the window 16 of sections B, C and D will register with the opening 39 of the bottom of the casing and the roller 26 respectively. Downward pressure 50 is now applied to the handle 1 forcing the type of the wheel 8 upon a book, check or other receipt as is illustrated in Fig. 4 where an entry is to be made which latter is placed upon a suitable support below the stamp casing. As the roller 26 is supported by the legs 34 the type of the wheels 9 will also be moved in contact with the tape thereupon printing the registered numbers of all the sections A, B, C and D thereon. The type 55 wheels forming section A and the tape 23 engaged on the winding roll 27 are automatically moved forward ready for the next operation through the pawl and ratchet mechanism formally described.

Obviously, my improved device is capa-

ble of many modifications, and those modifications that are within the scope of my claims, I consider within the spirit of my invention.

I claim:

1. A device of the character described comprising a casing, sets of type impressing wheels, mounted within said casing, a tape arranged in the casing adjacent one of said sets of type impressing wheels, a resilient support for the casing, having a portion extended within the latter, and means carried by the extended portion of said support and engageable with the tape for carrying the same into contact with its adjacent type wheels to receive an impression therefrom upon depressing said casing on its support. 70

2. A device of the character described comprising a casing, an adjustable printer mounted within the casing, a tape arranged in the casing adjacent said printer, a resilient support for the casing arranged upon the under side thereof and having a portion extended within said casing, and means carried by the extended portion of said support and engageable with said tape for carrying the same into contact with the printer to receive an impression therefrom upon depressing of the casing on its support. 85

3. A device of the character described comprising a casing having an opening formed in the under side thereof, two cooperatively associated sets of type impressing wheels mounted within the casing, one of said sets of type impressing wheels being positioned to register with the opening formed in the under side of said casing, a tape arranged in the casing adjacent the remaining set of type impressing wheels, a resilient support carried by the under side of the casing and having a portion extended therein and engageable with said tape, whereby upon depressing the casing, said resilient support will carry the tape into contact with its adjacent set of type wheels and allow the other set of type wheels registering with the opening formed in the under side of the casing to print upon an article placed outside of said casing. 100

4. A device of the character described comprising a casing, sets of type impressing wheels mounted within the casing, a tape arranged in the casing adjacent one of said sets of type impressing wheels, a resilient support for said casing having a portion extended within the latter, a pressure roll carried by the extended portion of said support and engageable with said tape for carrying the latter into contact with its adjacent type wheels upon depressing the casing, and means associated with said support and tape for actuating the latter upon returning of the casing to its normal position. 110

5. A device of the character described comprising a casing, a printer mounted within the casing, a tape arranged in the casing ad-

- jacent said printer, spring actuated legs mounted in the under side of the casing and having a portion extended within the latter, means secured to the extended portion of 5 said legs interconnecting the same, and a pressure roll supported by certain of said legs, engageable with the tape for carrying the latter into contact with its adjacent printer upon depressing the casing.
- 10 6. A device of the character described comprising a casing, a printer mounted within the casing, a movable tape arranged in the casing adjacent said printer, spring actuated legs mounted in the under side of the casing and having a portion extended within the latter, means secured to the extended portion of 15 said legs interconnecting the same, a pressure roll supported by the extended portion of certain of said legs and engageable with the tape for carrying the latter into contact with its adjacent printer upon depressing of the casing, and means associated with said legs and tape to move the latter with the up and down movement of 20 25 the casing.
